(57) CLAIM

The ornamental design for a jewelry setting/gemstone arrangement, as shown and described.

DESCRIPTION

FIG. 1 is a top view of a jewelry setting/gemstone arrangement showing my new design;

FIG. 2 is a bottom view of the jewelry setting/gemstone arrangement of FIG. 1;

FIG. 3 is a side view of the jewelry setting/gemstone arrangement of FIG. 1; and,

FIG. 4 is a perspective view of the jewelry/gemstone arrangement setting of FIG. 1.

The broken lines are provided for illustrative purposes only, and form no part of the claimed design.

1 Claim, 4 Drawing Sheets
